John H. Brincker - Design for Pen and
Pencil

Patinated brass

Des. 861

John H. Knapp, of New York, N.Y.
Letters Patent No. 861. Dated Jan'y 6. 1857.

The Schedule referred to in these Letters Patent and making part of the same.

To all whom it may concern.

Be it known that I,

John H. Knapp, of the City, County and State of New York, have invented a new and original design for an ever-pointed Pencil Case; and I do hereby declare that the following is a full, clear and exact description of the same, reference being had to the annexed drawing, making a part of this specification, said drawing being an elevation of a pencil case, showing my design.

Dec. 861

The case, which is represented by A, is made in the form of a cannon, the breech having a milled bead or projection a, around it. A milled bead b, is also formed around the breech just below the touch-hole or vent c, and a smaller plain bead d, is formed each side of the bead b. The muzzle has plain beads e, f, around it.

Near the centre of the case, or at the point, on cannons, where the trunnions are placed, a chased bead g, is formed and a milled bead h, is formed at each side of the chased bead g. A small plain bead i, is also formed each side of the chased bead g, between the bead g, and beads h, and a plain bead j, is formed around the case at the side of the milled bead h, nearest the vent c.

What I claim as new and desire to secure by Letters Patent, is,

Making the case A, in the form of a cannon, provided with the beads as shown and described, the whole forming a new and original design for a pencil case.
